UNITED STATES PATENT OFFICE

160,028

MAILBOX SUPPORTING BRACKET

Frank P. Spencer, Golden Valley, Minn.

Application June 9, 1949, Serial No. 3,147

Term of patent 14 years

(Cl. D33—3)

To all whom it may concern:

Be it known that I, Frank P. Spencer, a citizen of the United States, residing at Golden Valley, in the county of Hennepin and State of Minnesota, have invented a new, original, and ornamental Design for Mailbox Supporting Bracket, of which the following is a specification, reference being had to the accompanying drawing, forming part thereof.

Figs. 1 and 2 of the drawing are perspective views of a mailbox supporting bracket, showing my new design.

I claim:

The ornamental design for a mailbox supporting bracket, as shown.

FRANK P. SPENCER.
